CARTRIDGE BELT LINK GUIDE

Richard J. MacFarlane, Springfield, Mass., and
Harold E. Kershaw, Hartford, Conn.

Application May 2, 1946, Serial No. 666,780

7 Claims. (Cl. 89—33)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to improvements in feeding ammunition through machine guns and is directed more particularly to a link guide for such machine guns which use a disintegrating-link type ammunition belt.

It has occasionally been found in the manufacture of cartridges and in the loading of the same into belts that occasionally a bullet is forced into its cartridge case beyond the proper seating depth resulting in an overall cartridge length shorter than the minimum prescribed therefor. Cartridges of this nature are commonly referred to as "short rounds" and will invariably cause a failure to feed when loaded into a Browning type machine gun because the extractor will merely strike the base of the short round and push such forward until the bullet thereof strikes the conventional bunter plug at the front of the feedway. In addition to this failure to feed, possible injury to the nose of the bullet may occur as the result of striking the bunter plug and in the case of frangible ammunition used for training purposes, complete shattering of such bullets will, no doubt, take place.

Machine guns of the Browning type are normally adapted to use a disintegrating type of metallic belt link. Such links comprise a forwardly extending double loop and a rearwardly extending single loop. The single loop of one link is inserted between the double loop of an adjacent link and a cartridge is forced through the opening defined by coupling the links in such fashion. A plurality of cartridges and links assembled thus form a cartridge belt in whatever length may be desired. A conventional belt filling machine is normally used to load cartridges into link belt form and by the nature of its operation insures that all links are uniformly positioned on the cartridges with respect to the longitudinal axis thereof. The cartridges of course are presumably identical in shape and length.

It can thus be readily seen that if the links are uniformly guided through the feed channel of a machine gun, each cartridge held by the links will therefore be longitudinally positioned for proper extraction from the belt regardless of the overall length of the cartridge.

This locating feature of linked cartridges has heretofore been recognized in the construction of devices adapted to align cartridges in the feed-

2

way of a machine gun for proper extraction from the cartridge belt. However, such previous devices have been located in the gun above the cartridge belt and have therefore been subject to battering and scuffing as the belt is fed through the gun. But the device of this invention is so constructed as to lie along the floor of the transverse feed channel underneath the cartridge belt thereby offering a minimum of resistance to the feeding of such belt and decreasing the possibility of excess wear and breakage. In addition, positioning the device of this invention in the manner described positively assures no interference with the opening and closing of the gun cover, as occasionally occurred in other short round devices fastened to the cover or positioned above the ammunition belt.

Little or no attention has previously been paid to guiding the links out of the gun after extraction of a cartridge has taken place. In machine guns of the type with which we are here concerned, there is a short interval of time in which a link lies free in the feedway of the gun. On recoil of the gun, a cartridge is fully extracted from the links at an instant of time which is a little more than half of that required for completion of the rearward travel of the recoiling parts of the gun. It is then that the previously mentioned coupling of the links is broken and the links from which the cartridge has been extracted is free of the belt. After counterrecoil of the gun has begun, the next round in the belt is moved up to the extracting position in the feedway and by doing so pushes the free link along the feedway out of the gun. But during the short interval of time in which the link is free, it is subject to movement as a result of the vibration of the gun and in particular the shock of the recoiling parts striking the buffer at the end of the recoil stroke. The free link therefore tends to jump and twist in the feedway before such time as it is pushed out by the feeding of the next cartridge. As a result, such link may interfere with the feeding movement of the belt by jamming against the closed cover of the gun thereby causing a stoppage in the firing of the gun.

Modern practice, particularly with respect to machine guns intended for airplane use, requires that the feed mechanism and associated parts of the gun be adjustable so that the direction of feeding may be readily reversed without the addition or substitution of any parts. The guide unit of the present invention is symmetrical in shape and is therefore adapted to function equal-

ly well regardless of the direction of feeding of the gun.

Accordingly it is an object of this invention to provide a link guide for a machine gun whereby both the cartridges and links comprising an ammunition belt will be properly guided during the feeding operation of the gun.

It is a further object of this invention to provide an improved device for correctly positioning cartridges for positive extraction from an ammunition belt by using the forward edges of the foremost link as a locating point.

It is another object of this invention to provide a device for guiding links out of the feedway of a machine gun so as to prevent link jams therein.

It is still another object of this invention to provide a link guide which functions equally well in a machine gun regardless of the direction in which the belt is fed therethrough.

It is a particular object of this invention to provide a link guide for a machine gun such as disclosed in U. S. Patent No. 1,628,226 to John M. Browning.

The specific nature of the invention as well as other objects and advantages thereof will clearly appear from a description of the preferred embodiment as shown in the accompanying drawings in which:

Fig. 1 is a perspective view of a portion of a machine gun illustrating the link guide applied thereto;

Fig. 2 is a sectional detail view taken on a vertical plane through line 2—2 in Figure 1 showing a cartridge in extracting position on the link guide of the present invention;

Fig. 3 is a section taken along line 3—3 in Fig. 2;

Fig. 4 is a perspective view of the link guide; and,

Fig. 5 is a perspective view showing a fragment of a cartridge belt.

The operation of the feed mechanism of the Browning type machine gun herein mentioned is fully described in Patent No. 1,628,226 to John M. Browning. For purposes of explaining the advantages and features of the present invention, reference will be made to details of such feed mechanism, but it should be understood that this invention is also applicable to any machine gun using a metallic disintegrating-link type ammunition belt in the manner similar to that disclosed in the Browning patent.

The machine gun shown in Fig. 1 includes a receiver casing 2 having a transverse feed channel 4 for the passage of a linked belt 6 comprising cartridges 8 and links 9. A cover 11 is pivoted to casing 2 as shown at 13 and is in the open position in Fig. 1. An axially movable breech bolt 10 is provided with a pivotally mounted extractor 12 for withdrawing cartridges 8 from belt 6. Bolt 10 serves in the well known manner to cause actuation of a feed slide 3 which moves belt 6 through feed channel 4 by means of a pawl 5. Slide 3 is located in cover 11 as shown.

On each side of the gun there is provided a bracket 14 secured to receiver casing 2 so as to form the end portions of feed channel 4. Associated with the bracket 14 at the entrance end of feed channel 4 is a belt holding pawl (not shown) designed to engage successive cartridges to prevent any possible backward movement of belt 6. On the opposite end of the feed channel 4 the bracket 14 is provided with a front cartridge stop 18, a link stripper 20 designed to prevent

excessive twisting of belt 6 when a cartridge is extracted therefrom, and a rear cartridge stop 21. Stops 18 and 21 and link stripper 20 limit the feeding movement of cartridge belt 6 and 5 are held in place by a longitudinal retaining pin 16 extending through the apertures in bracket 14. Another retaining pin 16 is provided in the bracket 14 at the entrance end of feed channel 4. It 10 will be understood that while parts 3, 18, 20, and 21 are in the relationship shown when the gun is intended for left hand feeding, these same conventional parts are interchangeable to opposite sides of the gun when it is desired to feed the belt from the right hand side of the gun.

15 Shown in Fig. 5 is a fragment of cartridge belt 6 including a cartridge 8 and links 9 in the relationship previously mentioned. Cartridge 8 is provided with an annular groove near the rear end which defines a shoulder 7 adapted to be engaged by extractor 12.

20 The link guide 25 of this invention is shown particularly well in Fig. 4 and consists essentially of a strip of spring-like metal having an elongated body portion 30 and opposite end portions 25 which are bent downwardly and then inwardly towards one another so as to define U-shaped curves 32 with open sides facing one another. Body portion 30 is formed so that its central rear portion 33 is curved convexly to project rearwardly of the opposite U-shaped end portions 32. The central rear portion 33 is also flared upwardly so as to be in a higher horizontal plane than the rest of body portion 30. The entire body portion 30 is also slightly convexly curved so as to be in 35 a higher vertical plane than the opposite U-shaped ends 32.

25 To assemble the link guide 25 to the gun, one U-shaped end 32 is placed so as to engage retaining pin 16 on one side of feed channel 4 and 40 the other retaining pin 16 in the bracket at the entrance end of feed channel 4 is partially withdrawn and then reinserted to engage the opposite U-shaped end portion 32 of the link guide. It should be understood that it is immaterial 45 which retaining pin first engages a U-shaped end portion since the link guide is symmetrical and when assembled to the gun is adapted to function equally well in whichever direction feeding of the belt takes place. In either case, the link guide 50 25 overlies the floor of feed channel 4 with the upraised central portion 33 facing the bolt 10 and extractor 12 of the gun.

55 As linked belt 6 is moved through feed channel 4 by feed slide 3, the foremost cartridge 8 presses down on the upraised central portion 33 thereby insuring that the free edge thereof positively abuts the forward edge of the foremost cartridge link 9. Thus cartridge 8 is properly longitudinally positioned in the feedway to permit engagement 60 of the extractor 12 with the annular shoulder 7. Regardless of the overall length of cartridge 8, such cartridge is properly located due to the uniform positioning of the cartridge links 9 thereon.

65 As cartridge 8 is withdrawn from belt 6 by extractor 12, the foremost link 9 is set free from the remainder of belt 6 as previously described. But when the link guide 25 of this invention is present in the gun, the foremost link 9 is kept 70 from twisting or turning in feed channel 4 by the rear edge of body portion 30 lying in front of the forward edge of such link. Furthermore when cartridge 8 has been withdrawn from belt 6, the pressure on central portion 33 is relieved allowing the link guide 25 to return to its original

bowed shape. Thus the rear edge of body portion 38 rises even higher in front of the link 9 and prevents undue twisting or turning thereof with the consequent jamming in feed channel 4 against cover 11. And as the next successive cartridge is fed into chambering position, it pushes free link 9 out of feed channel 4. Proper guidance of free link 9 is insured by the remainder of the rear edge of body portion 38.

Such guiding effect is particularly true in the case of the last cartridge in the belt. In such event there are two free links remaining after the cartridge has been extracted therefrom. Without the link guide to keep such links from twisting, a link jam is highly probable especially in high speed guns.

It can thus be readily seen that not only does the rear edge of body portion 38 guide the links coming out of feed channel to prevent link jams therein, but also guides the incoming links containing cartridges so as to properly position such cartridges for positive extraction from the linked belt.

It will also be appreciated that the link guide of this invention is simple to manufacture and easy to assemble and disassemble.

We claim:

1. A link guide for a disintegrating-link belt fed machine gun comprising, an elongated body portion having inwardly facing opposed U-shaped ends whereby said link guide is mounted to the gun, said body portion bowed so as to be elevated above the plane of said U-shaped ends, said body portion having a convexly curved central rear portion upwardly inclined so as to prevent an elevated free edge in a plane higher than the remainder of said link guide.

2. In a belt fed machine gun having a transverse feed channel adapted to receive a linked belt of cartridges, a link guide mounted on the feedway adjacent the forward side thereof, said link guide comprising an elongated body adapted to lie beneath the linked belt of cartridges, and U-shaped ends facing inwardly and oppositely for mounting said link guide to the gun, said body having a convexly curved central rear portion upwardly inclined so as to present an elevated free edge adapted to lie in front of the foremost link in the belt of cartridges.

3. In a belt fed machine gun having a transverse feed channel terminating in bracket ends, each apertured to receive a longitudinal pin, and a belt of linked cartridges disposed in the feed channel, a unitary member comprising, an elongated body adapted to lie along the feed channel beneath the belt of cartridges, and U-shaped ends facing inwardly and oppositely for engagement with the longitudinal pins whereby said unitary member is mounted to the gun, said body having a convexly curved central rear portion inclined so as to present an elevated free edge, all adapted and arranged whereby said elevated free edge bears against the forward edge of the link surrounding the foremost cartridge to properly position such cartridge in the feed channel for extraction from the belt.

4. A device as described in claim 3 but wherein said unitary member is bowed so as to provide resiliency thereto when depressed by the belt of cartridges, said U-shaped ends therefore slidably engaging the longitudinal pins.

5. In a belt fed machine gun having a transverse feed channel adapted to receive a linked belt of cartridges, means for feeding the linked belt through the feed channel, and means for extracting cartridges from the linked belt, the improvement comprising a resilient unitary member having an elongated body adapted to lie along the transverse feed channel beneath the linked belt of cartridges, said elongated body having the opposite ends thereof bent downwardly and inwardly to form U-shaped passages adapted for mounting said unitary member to the gun, all adapted and arranged whereby the links containing cartridges are properly guided into the feed channel of the gun during the feeding operation thereof and whereby the links freed from the belt when extraction of a cartridge has taken place are properly guided out of the feed channel to prevent link jams therein.

20 6. In a belt fed machine gun having a feed channel adapted to receive a linked belt of cartridges, the links uniformly positioned on the cartridges, means for feeding the linked belt of cartridges through the feed channel, and means 25 for extracting the cartridge from the linked belt, the improvement comprising a resilient unitary member having an elongated body adapted to lie along the transverse feed channel beneath the linked belt of cartridges, said elongated body having the opposite end portions thereof bent downwardly and inwardly to form U-shaped passages adapted for mounting said unitary member to the gun, said elongated body having a rear central portion convexly curved and inclined 30 upwardly so as to present a free edge elevated over the remainder of said body, all adapted and arranged whereby said elevated free edge longitudinally positions each cartridge in the feed channel for extraction from the linked belt regardless of the overall length of the cartridge and 35 whereby the remainder of said body guides the links through the feedway so as to prevent link jams therein.

40 7. In a belt fed machine gun having a transverse feed channel adapted to receive a linked belt of cartridges, and means for feeding the linked belt across the feed channel in either a left hand or right hand direction, the improvement comprising a symmetrical resilient unitary member having an elongated body adapted to lie along the transverse feed channel beneath the linked belt of cartridges, said elongated body having the opposite ends thereof bent downwardly and inwardly to form U-shaped passages adapted for mounting said unitary member to the gun, said elongated body having a rear central portion convexly curved and inclined upwardly so as to present a free edge elevated over the remainder of said body, all adapted and arranged whereby said elevated free edge longitudinally positions each cartridge in the feed channel for proper extraction from the linked belt and whereby the remainder of said body guides the links through the feed channel so as to prevent link jams therein, both features unaffected by the direction in 50 which the linked belt may be fed through the feedway.
